UNITED STATES PATENT OFFICE.

GEORGE W. DIXON, OF LYNN, ASSIGNOR TO THE AMERICAN SHOE TIP COMPANY, OF BOSTON, MASSACHUSETTS.

SHOE-TIP.

SPECIFICATION forming part of Letters Patent No. 507,798, dated October 31, 1893.

Application filed August 11, 1892. Serial No. 442,807. (No model.)

To all whom it may concern:

Be it known that I, GEORGE W. DIXON, a citizen of the United States, residing at Lynn, in the county of Essex and State of Massachusetts, have invented certain new and useful Improvements in Shoe-Tips, of which the following is a specification, reference being had therein to the accompanying drawings.

Shoe tips of leather are commonly made by skiving the edge of the piece of leather then folding the skived edge on itself and cementing it down prior to forming or molding the tip in the machine which is employed for this purpose. The upwardly projecting portion 10 of the tip which protects the upper is subjected to the severest wear, and the upper edge of this upwardly projecting portion is apt to be the first part of the tip to wear through. Since this upper edge is formed by 15 folding upon itself the skived edge of the original piece of leather from which the tip is made when substantially one-half of the total thickness of the tip is worn away it is worn through to the fold and leaves this edge in a 20 ragged and poor condition, giving the shoe a 25 shabby appearance.

My invention has for its object to provide a tip which shall obviate these objections, and it consists in a tip made from a piece of material, the edge of which has been skived in the peculiar manner hereinafter set forth and folded upon itself so that substantially the full thickness of the material is preserved at the wearing points, all as hereinafter described.

In the accompanying drawings to which reference will be made in the following description, Figure 1 is a perspective of the toe of a shoe showing a tip in position. Fig. 2 is 30 a sectional view of a piece of leather used in making a tip, showing the skiving commonly employed and indicating by dotted lines the method of folding the skived edge. Fig. 3 is a similar view of a piece of leather such as is 35 employed in making a tip embodying my invention. Fig. 4 is a sectional view of a finished tip of common construction such as is made from a piece of leather skived and folded, as shown Fig. 2. Fig. 5 is a similar view 40 of a tip embodying my improvement.

As the method of manufacturing tips is

well known and as tips embodying my invention differ from those heretofore made only in the construction of the edge of the upwardly projecting portion I will confine my description to the construction of this edge. At A, Fig. 1, I have shown a shoe tip of common form, applied to a shoe. The upwardly projecting portion which protects the upper is subjected to the greatest wear. The upper 55 edge of this portion is commonly made by skiving the leather, as shown at *k*, Fig. 2, on the flesh side and folding the skived portion on itself as shown by the dotted lines in said figure. In this way only the blacked side of 60 the leather shows at the edge and a finished edge is produced. It will be noted however that the thickness of the leather in front of the line of fold *t* is considerably lessened by the skiving operation, and when this leather is 65 worn through to the line of fold the value and appearance of the shoe is impaired. To avoid this difficulty I skive the edge of the piece of leather from which the tip is made, as shown Fig. 3, that is, instead of a straight bevel as 70 shown Fig. 2 a shoulder *b*, is formed on the flesh side of the stock and the stock is beveled or skived from this shoulder to a feather edge, as shown at *f*. This leaves the stock on and behind the shoulder and forms a thin 75 skived edge in front of the shoulder which serves to fold over and give the desired finish. By the old method of preparing the stock the skived edge which was folded over was unnecessarily thick for the purpose of 80 obtaining a finish while the line of fold was carried forward and the stock in front of the line of fold was comparatively thin and less able to resist wear. When the edge of a piece of leather, skived in the improved manner 85 herein set forth, is folded to form the edge of the tip the parts assume the position shown Fig. 5, and the upwardly projecting portion of the tip is preserved in its original thickness or substantially so, from its base near 90 the sole to the top or upper edge thereof. The full body substantially of the stock used for the upwardly projecting portion of the tip remains in front of the line of fold, and not only is the stock differently located with reference to the line of fold by reason of the difference in cutting or skiving the edge of the 95 100

piece of leather but slightly more stock is thrown into the upwardly projecting portion of the tip which enables the tip to be finished under greater pressure thus increasing the 5 solidity and density of the stock in this portion of the finished article and rendering it more durable. It will also be noted that there is an increase in the total thickness of the stock from the base to the top of the upwardly projecting portion of a tip embodying 10 my invention, and this is important as the wear is greatest toward the top.

A shoe tip made in accordance with my invention is much easier to manufacture in that 15 the skived edge is easily and accurately folded over the shoulder *b*, the shoulder serving as a guide from which to fold the material. When no shoulder is employed as in the old method the edge which is folded by machine 20 is apt to be folded at a different point in different tips. That is, sometimes a greater width of the edge is folded over than at other times thus producing an irregularity and lack of uniformity in the manufacture. When 25 however, the material is skived from a shoulder as heretofore described this irregularity disappears and a regular and uniform fold is easily obtained which is important.

What I claim is—

1. A compressed, molded shoe tip consisting of a strip of material which is formed with a beveled shoulder *b* on its rear side, and with a flap of reduced thickness extending from said shoulder to one edge of the strip, said flap being turned back on the main thickness of the strip on the line of fold which is determined by the said shoulder, and the tip being formed and molded to shape by pressure, substantially as and for the purposes set forth. 30

2. The process of manufacturing shoe tips which consists in first forming a beveled shoulder on one side of a strip of material and skiving the said material from the said shoulder to a feather edge on one edge of the 35 strip, then folding the flap of reduced thickness thus formed over the shoulder on a line which is determined by the said shoulder, and finally molding the tip to shape under pressure, substantially as set forth. 40

In testimony whereof I affix my signature in presence of two witnesses.

GEORGE W. DIXON.
